(57) **CLAIM**

The ornamental design for a pocket for a diaper, as shown and described.

DESCRIPTION

FIG. 1 depicts a rear perspective view of a pocket for a diaper showing my new design;

FIG. 2 depicts a front elevational view of the pocket for a diaper based on FIG. 1;

FIG. 3 depicts a rear elevational view of the pocket for a diaper based on FIG. 1 and the reverse view of FIG. 2;

FIG. 4 depicts a top plan view of the pocket for a diaper based on FIG. 1;

FIG. 5 depicts a bottom plan view of the pocket for a diaper based on FIG. 1 and the reverse view of FIG. 4;

FIG. 6 depicts a right elevational view of the pocket for a diaper based on FIG. 1; and,

FIG. 7 depicts a left elevational view of the pocket for a diaper based on FIG. 1 and the reverse view of FIG. 6.

The broken lines shown in FIGS. 1-7 illustrate portions of the pocket for a diaper that form no part of the claimed design.

1 Claim, 7 Drawing Sheets
